G. E. RANDLES

WASHING MACHINE

Filed June 25, 1924

Inventor:
George E. Randles,
by Alfred T. Bassett,
His Attorney.

UNITED STATES PATENT OFFICE.

GEORGE E. RANDLES, OF CLEVELAND, OHIO, ASSIGNOR TO THE FOOTE-BURT COMPANY, A CORPORATION OF OHIO.

WASHING MACHINE.

Application filed June 25, 1924. Serial No. 722,394.

To all whom it may concern:

Be it known that I, GEORGE E. RANDLES, a citizen of the United States, residing at Cleveland, in the county of Cuyahoga and 5 State of Ohio, have invented certain new and useful Improvements in Washing Machines, of which the following is a specification.

The present invention relates to washing 10 machines and especially to washing machines of the suction cup or pounder type.

The primary object of my invention is to provide an improved arrangement for preventing leakage of water down along the 15 plunger rod and an arrangement whereby should any leakage occur, the drops of water will be prevented from finding their way into the gear casing.

For a consideration of what I believe to 20 be novel and my invention, attention is directed to the accompanying description and the claims appended thereto.

In the drawing, Fig. 1 is a side elevation, 25 partly in section, of a washing machine embodying my invention; Fig. 2 is a detail sectional view of certain parts on a larger scale; Fig. 3 is a sectional view of the suction cup mounting and plunger rod packing; Fig. 4 is a detail view of the suction 30 cup mounting, and Fig. 5 is a sectional view of a packing.

Referring to the drawing, 6 indicates a gear casing supported by legs 7 and containing mechanism for actuating the plunger rod 8. This mechanism may be of any suitable type. For example, it may be of the character disclosed in my Patent Number 1,520,886, dated December 30, 1924. In the 35 top of the casing is a depression 9 providing a top wall 10 through which plunger rod 8 extends and in vertical spaced relation to wall 10 is a block 11 suitably attached to the top wall of casing 6 by a number of screws 12. Block 12 is provided with a threaded 40 opening into which is screwed the lower end 13 of a stationary tubular post 14. Mounted on gear casing 6 is a frame 15 in which a tub 16 is mounted, the tub sitting on top of casing 6. The center of the bottom of the 45 tub sits on block 11 and is held thereon by a flange or collar 17 on post 14, a packing 18 being provided between the tub and block to effect a water tight joint.

Tubular post 14 is of a diameter somewhat 50 greater than plunger rod 8 and at its upper

end it is provided with a neck 19 with which the rod has a sliding fit. The outer surface of neck 19 is threaded to receive a packing nut 20 and between this nut and the upper end of post 14 is located a packing 21. This 60 packing is of special construction, (see Fig. 5) and comprises an inner portion 22 of fibrous material which has been treated with a suitable lubricant and an outer portion 23 of rubber. I have found that by using a 65 packing member of this type a much tighter joint is obtained because when the packing nut 20 is screwed down to compress the packing, the resiliency of the rubber portion of the packing serves to hold the fibrous 70 portion of the packing in close contact with the plunger rod and permits it to conform to the contour of the rod. At the same time, however, the rubber portion permits the packing to yield enough so as not to bind 75 on the rod.

Now, with a machine of this type, it is important that if any water leaks past packing 21 such water should be prevented from running down the plunger rod and finding 80 its way into the gear casing, and a feature of my invention is the improved means which I have devised for preventing this from occurring. According to this feature of my invention, I provide on the plunger rod a 85 member 24 which I term an umbrella. This umbrella has a smooth top wall 25 and a depending skirt or flange 26, the lower end of which is beveled to provide a sharp edge 27. In the present instance 90 plunger rod 8 is shown as being formed in two parts connected by a threaded coupling member 28 and umbrella 24 is shown as being formed as a part of the coupling member and as being held between the adjacent ends of the two plunger rod sections, the top and bottom walls of the umbrella having smooth plane parallel faces with which the ends of the plunger rod sections engage. Umbrella 24 is of a diameter less 95 than the inside diameter of tubular post 14 so that there is a clearance between the outer wall of the umbrella and the inner surface of the post.

The umbrella is located on the plunger rod at a point such that upon the down stroke of the rod it passes below the lower edge of the end 13 of post 14. At the point where plunger rod 8 passes through top wall 10 there is provided a metallic pack- 105 110

ing sleeve 29 the upper end of which projects well above the top surface of such wall and in the top of wall 10 there is provided an annular depression or pocket 30. 5 Both umbrella 24 and end 13 are of greater diameter than packing sleeve 29 as will be seen from an inspection of Fig. 2.

With this arrangement, any water which leaks past packing 21 will run down the 10 plunger rod until it strikes the top of the umbrella. It will be then deflected outwardly by the umbrella and will run down its outer surface and gather on the lower edge of skirt or flange 26 in the form of 15 drops. These drops will cling to the outer lower end of the skirt or flange on account of the sharp edge 27 thereon. On the down stroke of the plunger rod these drops are carried down below the end 13 of post 20 14, and then on the up stroke they are wiped off the edge of the umbrella by the lower edge of end 13 and drop off of it and run into pocket 30. The umbrella thus serves as a means for transferring the water from 25 the plunger rod to the tubular post. The beveled edge on the umbrella prevents the drops of water from running in toward the plunger rod and so finding its way to the top of packing sleeve 29. Of course, drops of water may transfer from 30 the umbrella to the inner surface of tubular post 14 and if this occurs such drops will run down the surface of the post and drop off into pocket 30. In this connection it 35 will be understood that the quantity of water likely to leak past packing 21 is in any event small and any that collects in pocket 30 will readily evaporate.

By collecting the water in a pocket it is 40 prevented from running down the gear casing and streaking it, thus marring its appearance, and from running onto the floor. In actual practice, I have found that a clearance of about $\frac{1}{2}$ of an inch between 45 the umbrella and the inner surface of post 14 is satisfactory.

The prevention of leakage of any water into the gear casing is particularly important in case the actuating mechanism 50 within the gear housing is lubricated with oil because the mixture of water with the oil tends to destroy its lubricating qualities. By my improved construction, I prevent any water finding its way into the gear casing. 55 At the same time the arrangement is simple in structure and can be embodied in a machine at low cost.

Referring now to the suction cup or bell mounting, 31 indicates a yoke which is 60 justably mounted on the upper end of plunger rod 8 by a spring-pressed pin 32 adapted to engage any one of several spaced openings 33 in the upper end of the plunger rod. At the ends of the yoke arms are 65 downwardly facing sockets 34 which are

closed at the tops by smooth top walls 35 which are rounded so as to present a pleasing appearance and leave no sharp corners. Extending through the walls forming sockets 34 are openings 36 which are threaded 70 at their inner ends and are adapted to receive screws or pins 37. The suction cups or bells 38 are riveted or otherwise suitably attached to flanges 39 on the lower ends of tubular stems 40. Stems 40 are provided 75 with internal shoulders 41 upon which seat the lower ends of springs 42, the upper ends of such springs engaging nuts or plugs 43 which screw into the upper, open ends of the stems. Nuts 43 are provided with 80 downwardly open slots 44 which stand in line with elongated slots 45 in stems 40 and with openings 36, screws 37 passing through slots 44 and 45. Slots 44 are of a depth such that screws 37 can just pass through 85 them above the tops of springs 42, the springs being thus in engagement wth the screws. The springs are held under the desired compression by nuts or plugs 43. The slots 45 in stems 40 are of a length such 90 as to permit of the desired axial movement of stems 40 in sockets 34. When the upward pressure on the suction cups is excessive, springs 42 yield to permit stems 40 to move upward in sockets 34, springs 42 being compressed against the pins 37.

This spring mounting has the advantage that it is simple in structure, is easy to assemble, and leaves the yoke with a perfectly smooth exterior and without cracks or joints into which water can leak. In assembling the yoke structure, the springs 42 are placed in stems 40 after which nuts 43 are screwed into position to hold the springs compressed, the nuts being turned 100 to bring slots 44 into line with slots 45. The stems are then inserted into sockets 34 and screws or pins 37 put into position. Thus the operation of assembling can be quickly and easily performed. The spring mounting for the suction cup is not claimed here- 105 in as it forms the subject matter of my application, Sr. No. 752,836, filed November 29, 1924.

In accordance with the provisions of the 110 patent statutes, I have described the principle of operation of my invention, together with the apparatus which I now consider to represent the best embodiment thereof, but I desire to have it understood that the apparatus shown is only illustrative and that the invention may be carried out by other means.

What I claim as a new and desire to 115 secure by Letters Patent of the United States, is:-

1. In a suction cup washing machine, the combination of a tub, a tubular post therein, a plunger rod which extends up through the post in spaced relation to the 120

wall of the post, and means carried by the plunger rod for transferring water from the rod to the inner surface of the tubular post.

2. In a suction cup washing machine, the combination of a tub, a tubular post therein, a plunger rod which extends up through the post in spaced relation to the wall of the post, and an umbrella on the rod for transferring water from the rod to the tubular post.

3. In a washing machine, the combination of a gear casing, a tub located above it, a tubular post in the tub, a plunger rod which projects up through the top of the gear casing and said post, a pocket in the top of said gear casing surrounding the rod, and means carried by the rod for deflecting water leaking along the rod into said pocket.

4. In a washing machine, the combination of a gear casing having a wall provided with a depression, a tub mounted on the

casing, a tubular post in the tub the lower end of which terminates above the top wall of said depression, a plunger rod which projects up through the top wall of said depression, and through the tubular post, and an umbrella on the rod which moves from a point below the lower end of the tubular post up into the post, said umbrella serving to transfer water from the plunger rod to the tubular post.

5. In a suction cup washing machine, the combination of a tub, a tubular post therein, a plunger rod which extends up through the post in spaced relation to the wall of the post, and an umbrella on the rod for transferring water from the rod to the tubular post, said umbrella having a sharp lower edge.

In witness whereof, I have hereunto set my hand this 20th day of June, 1924.

GEORGE E. RANDLES.
